Primary Examiner — Kevin K Rudzinski*Assistant Examiner* — Paul D Bohannon*(74) Attorney, Agent, or Firm* — Shook, Hardy and Bacon L.L.P.(57) CLAIM

The ornamental design for a garment, as shown and described.

DESCRIPTION

FIG. 1 is a front view of a garment showing my new design; FIG. 2 is a rear view thereof; FIG. 3 is a first side view thereof; FIG. 4 is a second side view thereof; and, FIG. 5 is a front, perspective view thereof.

The even-length broken lines are directed to environment, represent unclaimed subject matter, and form no part of the claimed design.

The contrast in shading represents a contrast in appearance only and does not represent any particular color, material, texture or finish.
